US00D541012S

(12) United States Design Patent (10) Patent No.: US D541,012 S
Gottehrer (45) Date of Patent: * Apr. 24, 2007

(54) BIB

(76) Inventor: Jonathan M. Gottehrer, 198
 Dartmouth Dr., 2nd Floor, Hicksville,
 NY (US) 11801

() Term: 14 Years

(21) Appl. No.: 29/252,476

(22) Filed: Jan. 23, 2006

(51) LOC (8) Cl. 02-02

(52) U.S. Cl. D2/864

(58) Field of Classification Search D2/860-864,
 D2/853, 857; 2/455, 456, 463, 464, 46, 48-49.5
 See application file for complete search history.
